UNITED STATES PATENT OFFICE.

AUGUST WILLIAM BRATER, OF NEW YORK, N. Y.

SIPHON CONTROL DEVICE.

1,416,603.

Specification of Letters Patent. Patented May 16, 1922.

Application filed August 20, 1920. Serial No. 404,930.

To all whom it may concern:

Be it known that I, AUGUST W. BRATER, citizen of the United States, residing at New York city, in the county of New York and 5 State of New York, have invented new and useful Improvements in Siphon Control Devices, of which the following is a specification.

This invention relates to siphon control 10 devices, and one of the principal objects is to produce a device of this nature which shall be simple of construction, cheap to manufacture, and efficient for the purpose for which it is designed.

15 Another object is to provide a siphon which will not clog from sediment in the liquid flowing therethrough.

Another object is to provide a device for holding a siphon tube so that a kink may 20 be readily produced in the tube for cutting off the flow.

Another object is to provide a device of 25 this nature with means whereby the tube may be held in a kinked condition.

Another object is to provide automatic 30 means for effecting a kinking of the tube by bending or folding a portion of the tube upon itself.

With these and other objects in view, the 35 invention consists in certain novel construction and combinations and arrangements of parts, the essential elements of which are hereinafter fully described and claimed, and are shown in the accompanying drawing comprising two sheets, in which:

Figure 1 is a side elevation of my improved siphon control device arranged for automatically shutting off the flow of liquid, the parts being shown in the position assumed when the flow is unobstructed.

Figure 2 is a similar view but showing the parts moved to position to obstruct the flow of the liquid.

Figure 3 shows a spring controlled device 45 for a portable cut-off adapted for use on fountain syringes.

Figure 4 shows a form of lever control for the cut-off.

Figure 5 shows a weight used to operate 50 the cut-off as in stationary use.

Figure 6 shows a spring trip for cutting off the flow when a certain weight of liquid has been deposited on a scale or for like purposes.

55 Figure 7 is a view of a modified form of the device shown in Figure 1.

Figure 8 is the device as embodied in a portable control for fountain syringes and the like.

Figure 9 shows a device similar to Figures 60 1, 2 and 7 but for producing a single kink.

Figure 10 represents a modified form of single kink device.

Like characters of reference in all views refer to like parts.

Referring particularly to the form of the invention shown in Figures 1 and 2, 1 represents a standard or support which may be of the kind shown in the drawings or of any other suitable form. Adjustably supported upon this standard is a frame structure 2 having a depending arm 3 which is bent into or otherwise formed with a horizontally extending portion 4 which has its central portion cut away at 5 to permit the 75 passage of the neck of a float member 6. Secured in the side of member 3 is a pair of screws, nails or similar headed members 7 which are adapted to co-operate with respective bayonet slots 8 in a member 9. 80 Member 9 is a piece of springy metal which is folded at its ends and formed at 10 and 11 to support a rubber hose or tube 12 which forms a segment of a circle at 13. A member 14 is provided with a pair of upwardly 85 bent flanges 15 and with a pair of downwardly bent flanges 16. The neck of the float member 6 is extended up through an aperture in member 14 and is provided with a head 17 which secures member 6 to member 14. Flanges 16 are pivoted at 17^a so as to permit an upward swing of member 14 and member 14 is provided with a bent up portion 17^b adapted to limit such swing.

Pivoted to member 4 is a frame member 95 18 which comprises a pair of side arms 19 connected by a cross-bar 20. A pair of wires 21 connect pivotally with arms 19 and the flanges 15.

It will readily be seen that if the float is 100 placed in a vessel and the tube 12 conducts liquid into that vessel, that when the level of the liquid rises to the desired height it will raise the float 6 and thereby the table 14 so that the wires 21 will move the arms 105 19 about their pivots until the cross bar 20 presses on the arcuate portion 13 of the tube so as to effect a kinking thereof substantially as shown in Figure 2. It will readily be understood that if desired the member 9 110 can be detached from the member 3 and in this condition forms a portable cut-off for

the tube in the operation of which cut-off the tube is pushed in by hand at 13 and hooked over an outstanding finger 40 formed on the edge of the member 9.

- 5 In Figure 3 is shown a portable cut-off in which a frame member 22 is provided with tube holding portions 23 and 24 and at its center is provided with a slot 25 through which protrude the ends of a compressible 10 spring 26 which will normally hold the tube in the open condition as shown in full lines but upon pushing in the portion 13 of the tube to the dotted line position, the spring will expand as shown in dotted lines and 15 hold the tube in its kinked position for effecting a cut-off.

In the form of the device shown in Figure 4 a similar frame member to that used in Figure 3 is provided, and to the portion 24 20 there is pivoted and arm 27 which passes around the tube at 28 and which is provided with a finger piece 29. Near its pivot, arm 27 is provided with a finger 30 which is adapted to operate against a spring finger 25 31 bent up from member 24 so as to hold the arm 27 in either the full line position or the dotted line position. By pressing finger 29 toward the frame member 22 the tube portion 13 may be kinked to effect the cut-off and will be held in this condition by the 30 co-action of the fingers 30 and 31 until member 29 is moved in the opposite direction.

In Figure 5 is shown a device similar to that in Figure 1 but in which a weight 32 35 mounted in the bracket 33 is adapted to control portion 13 of the tube. This style is best adapted for stationary use.

In Figure 6 a spring 34 is provided which is connected to a collar 35 mounted on the 40 portion 13 and which collar is provided with a loop 36 which is adapted to be fastened over a trigger diagrammatically shown at 37 and which may be tripped by an ordinary scale or weighing device in any suitable manner so as to release the spring 34 to draw member 35 in to thereby kink the portion 13 of the tube.

In Figure 7, a float and table are used as in Figure 1, but the tube is attached to the 50 table and as the float raises the table, the tube is moved to the dotted line position thereby forming a single fold or kink to close off the flow of the liquid.

In the modified form shown in Figure 8, 55 the device is similar to the member 9 shown in Figure 1 but is devoid of the apertures or bayonet slots 8 for supporting the member; and the structure is made of rigid stock instead of springy material. This device is 60 adapted for use on all sorts of portable devices such as fountain syringes.

In Figure 9 is shown a modified form of 65 the single kink device of Figure 7. As the float is raised, the table to which the tube is secured, moves the tube to the dotted line

position thereby kinking the same to shut off the flow.

In the form shown in Figure 10, the raising of the float causes the movement of the parts from their full line position to the 70 dotted line position thereby causing the bending or folding of the tube on itself as shown in dotted lines, whereby the flow of liquid is stopped.

Particular emphasis is laid on the fact 75 that while there are shown a number of ways of producing the result, the principle is the same in all,—viz., the producing of a single or double kink by bending a portion of a tube or folding the same upon itself. This 80 I consider to be my invention.

While I have described what I deem to be the most desirable embodiments of my invention, it is obvious that many of the details may be varied without in any way 85 departing from the spirit of my invention; and I therefore do not limit myself to the exact details of construction herein set forth, nor to anything less than the whole of my invention limited only by the ap- 90 pended claims.

What I claim is:—

1. The combination of a frame carrying inlet and outlet tubes attached continuously to a semi-circle of flexible tubing and provided with a finger to retain a double kink produced by moving said semi-circle of flexible tubing at its curved portion toward the center of curvature by folding or bending a portion of the tube on itself and thereby 95 controlling the flow of liquid through the device.

2. In a device of the class described, the combination of a flexible tube, a piece of springy material bent so as to form means 105 for supporting said tube in arc formation and provided with a finger for maintaining said tube in kinked condition.

3. In a device of the class described, the combination of a flexible tube, a piece of 110 springy material bent so as to form means for supporting said tube in arc formation and provided with a finger for maintaining said tube in kinked condition and also comprising means for readily securing said device to a support.

4. The combination of a frame carrying inlet and outlet tubes attached continuously to flexible tubing in curved formation including means for readily securing said frame 120 to a support whereby said flexible tubing may be moved at its curved portion by suitable means toward the center of curvature and forming thereby a double kink by folding or bending a portion of the tube on itself 125 for controlling the flow of liquid through the device.

5. In a device of the class described, the combination of a flexible tube, means for supporting said tube in arc formation, a float, 130

a pivoted member operable by said float, and means operable by said pivoted member for effecting kinking of said tube.

6. In a device of the class described, the combination of a flexible tube, means for supporting said flexible tube in curved formation, a pivoted member operable to effect kinking of said tube, a float, and a pivoted member operable by said float and adapted 10 to operate the first said pivoted member for effecting kinking of said tube.

7. The combination of a flexible tube, and means for holding said tube in curved formation whereby said tube may be moved at its curved portion toward the center of curvature to form a kink by folding or bending 15 a portion of the tube on itself for controlling the flow of liquid through said tube.

In testimony whereof I have affixed my signature.

AUGUST WILLIAM BRATER.
